WINDING MACHINE

Charles R. Sibley, Marblehead, Mass., assignor to
 Sibley-Pym Corporation, Lynn, Mass., a corporation of Massachusetts

Application June 27, 1940, Serial No. 342,743

10 Claims. (Cl. 242—3)

This invention relates to the manufacture of spherical cores, particularly cores for golf balls wound from elastic thread or ribbon.

In manufacturing certain types of golf balls for example there is a demand for a hard core of high resiliency and this is produced by winding under high tension the elastic thread of which it is composed. The higher the tension in winding the thread, the more difficult it is to maintain a uniform tension throughout the core and the more skill and precautions are required on the part of the operator and in the mechanical handling of the thread and core to prevent breakage.

The object of the present invention is to provide a winding machine capable of operation at high speed, requiring little skill on the part of the operator and capable of producing in commercial quantity cores harder and more resilient and more perfectly spherical than any hitherto available. While there is always danger of breaking a tensioned elastic thread in the winding operation, there is the further danger that if the thread has been chafed in handling, it may break under tension in the core even after the winding operation has been entirely completed. In the machine of my invention the handling of the elastic thread is such that this after-breakage is eliminated or reduced to a minimum. To this end an important feature of the invention consists in a novel tensioning mechanism including a brake-controlled drum of substantial diameter about which the elastic thread is led in passing to the core being wound. This construction is beneficial in that the application of tension to the thread is thus spread gradually over a substantial length and not concentrated in a limited length of thread; in other words, the thread is given a substantial length in which to accommodate and condition itself to the state of maximum tension.

Another feature of the invention consists in provision of means for transversely shifting the position of the thread upon the tension drum during the operation of the machine, a mode of operation beneficial from the wearing standpoint and also one which insures uniform treatment of the thread.

Still another feature of the invention consists in an indicator or signal for warning the operator whenever the tension on the thread drops below the desired degree of high tension. This eliminates the waste of winding cores which are below the required degree of hardness. While the machine is in operation the indicator of my

invention functions to warn the operator whenever the tension drops below the desired degree and the tension mechanism may be adjusted at once.

Other features of the invention will be pointed out hereinafter more in detail. In general these contribute to improve the smoothness of starting and stopping the machine, to the convenience of threading it and of placing the core in and removing it from operative position, and to the simplicity and compactness of the mechanism.

These and other features of the invention will be best understood and appreciated from the following description of a preferred embodiment

15 thereof selected for purposes of illustration and shown in the accompanying drawings in which,

Fig. 1 is a front view in perspective of the machine,

Fig. 2 is a fragmentary view in elevation, partly in section of the indicating device, and

Fig. 3 is a rear view in perspective.

In the drawings only so much of the machine is shown as is needed for a complete understanding of the present invention. The illustrated 25 machine is of the general type disclosed in U. S. Letters Patent No. 2,033,356, granted March 10, 1936, on an application of Arthur F. Pym, and for further details of construction reference may be had to that patent.

30 The winding machine has a frame which includes the vertical panel 10 from which the core supporting rolls 11 and 12 project in side by side horizontal alignment. An endless elastic apron 13 extends about and travels upon the rolls. It 35 is adapted to be driven by the inner roll 12 and in its bight supports and rotates the core which is to be wound. The inner roll 12 is carried by a driven shaft journaled in the panel of the machine frame in alignment with the motor

40 shaft 14 upon which is mounted a clutch 15 of any commercial construction, for example, that shown in said Patent No. 2,033,356. The clutch is thrown into and out of operation to drive the rotary roll 12 by a shipper lever 17 45 pivotally mounted on its upper end upon a bracket 16 projecting rearwardly from the flange of the panel 10. At its lower end the shipper lever is connected with a long spring 18, adapted to be adjusted in tension by the setting of a

50 screw 23 conveniently located in the panel 10 and having a hook upon its rear end to which the spring 18 is attached. The shipper lever 17 is moved in opposition to this spring by a horizontal rod 19 having at its rear end a yoke pivotally connected to the shipper lever and ex-

tending at its front end through the panel 10 and into contact with a pivoted contact piece 20. The latter is journaled to swing upon a transverse pin or spindle mounted in a bracket 21 fast to the face of the panel 10. The contact piece 20 is held by the action of the spring 18 through the rod 19 against the inner wedge-shaped face of a starting arm 22 mounted to swing about a horizontal stud projecting from the face of the panel 10 and having at its outer or left-hand end an operating handle. When the arm 22 is depressed by the operator the rod 19 is forced rearwardly with a smooth and easy motion and the shipper lever 17 is rocked to throw the clutch into operation and start the machine smoothly and without shock. Movement of the starting arm is limited by the bracket 21 which is shaped to enclose the end of the arm and confine its motion to appropriate limits.

The thread supply is provided by a spool or reel 25 removably mounted between the arms of a yoke-shaped carrier 26 supported upon a standard 27 above the panel 10. A brake shoe 28 is arranged to bear yieldingly upon the body of the thread upon the spool 25 so preventing overrunning as the thread is drawn therefrom. An elongated guide roll 29 is obliquely mounted in the base of the carrier 26. The roll is slightly longer than the spool and in position to deflect the elastic thread in passing from the spool to the tension drum 30. It is oblique in that it rotates on an axis which is neither parallel to the axis of the spool nor perpendicular to a line normal to the face of the panel 10 and it is thus effective to shift the path of the thread nearer to or further from the face of the panel according to the point at which the thread is drawn from the spool.

A tension drum 30 of substantial diameter is mounted upon the forward end of a horizontal shaft journaled in a boss 31 projecting rearwardly from the panel 10. The axis of the drum 30 is perpendicular to the face of the panel 10. At its rear end this shaft carries a flanged brake drum 32 surrounded by a brake band 33 one end of which is fast to a pin 34 set in the panel 10 and the other end of which is secured to a link rod 35. This link is connected at its lower end to a lever 36 pivotally mounted in the base of the frame and arranged to be operated by a vertical rod 37 which extends upwardly through the upper flange of the panel 10. Above the flange the operating rod 37 passes through an arm 39 pivotally mounted to swing about a horizontal axis and normally elevated by a compression spring 40. At its upper end the rod 37 carries an adjustable thumb nut 38. The spring 40 therefore tends always to lift the free end of the arm 39, lift the operating rod 37 and rock the lever 36 so as to tension the brake band 33 upon the drum 32 and retard turning of the tension drum 30. The degree of brake band tension may be regulated by adjusting the thumb nut 38 on the end of the rod 37. A tension spring 41 extends between the end of the lever 36 and a pin 42 projecting from the back of the panel and works in opposition to the spring 40. Accordingly, whenever the free end of the arm 39 is depressed by the operator the spring 41 rocks the lever 36 in a counter-clockwise direction and immediately releases the tension of the brake band so that the tension drum may turn freely and the operator is thus permitted to draw thread from the reel 25 to thread the machine, that is to say, to pass it with 1½ turns about the circumference of the

tension drum 30 and give it a preliminary turn or two about the core to be wound.

The tension drum 30 is made of aluminum in order to reduce its inertia and is a substantial diameter, that is to say, it is approximately three times the diameter of either of the core supporting rolls 12 or 13 and about three times the diameter of the completed core. It is also substantially larger than the brake drum 32. It is so located that the length of thread upon its circumference is always greater than the length of the thread between it and the core being wound. A tension drum of these general proportions is an important feature of my novel machine. It provides an arc of contact with the elastic thread of such length that slipping is practically eliminated even though the thread is not tensioned substantially upon the circumference of the drum at the leading-on point.

Preferably and as herein shown, the circumference of the drum tapers or flares outwardly and the result of this construction is to spread the strands of thread as they pass about the drum preventing them from overlapping and chafing or wearing on each other. The diagonal roll 29 moreover, leads the thread to the tension drum at a constantly varying point of contact as the thread is drawn from the different points in the length of the reel. This not only prevents wear on the tension drum but contributes to the smooth running of the mechanism.

As the thread leaves the tension drum 30 it passes upwardly and over a grooved guide roll 43 mounted for free rotation in the upper end of an arm 44 fast to the end of a shaft 45 projecting forwardly from the panel 10 and journaled therein. The arm 44 is urged toward the right or away from the core by its connection with tension indicating mechanism which will now be described and which is shown in detail in Fig. 2.

A bracket 46 having a longitudinal bore is secured to the front of the panel 10 behind the upper portion of the tension drum 30. In the bore of the bracket is disposed a longitudinally adjusted rod comprising an outer tubular section 47 and a solid inner rod section 48 carrying a check nut 49 at its right hand end and a flanged collar 50 at its left hand end. The effective length of the rod may be adjusted by screwing the inner rod section in or out of the tubular section 47 and the adjusted relationship may be fixed by means of the set nut 49. A compression spring 51 located within the bracket 46 and bearing against the end of the tubular section 47 tends to move the rod as a whole always toward the right in its bracket 46. The flange 50 engages the edge of the arm 44 and tends always to swing the arm in the same direction. At the extreme end of the rod 48 is provided a flange 52 which is engaged between a pair of projecting ears upon the upper end of a pivotally mounted pointer 53. An index pin 54 projects from the face of the panel 10 in line with the central or vertical position of the pointer.

It will be apparent that tension in the thread passing from the tension drum 30 to the core tends to swing the lever 44 toward the left and to rock the index end of the pointer 53 toward the right. The position of the arm 44 and the pointer 53 therefore depends upon the degree of tension in this portion of the thread. If the tension drops, the arm 44 is permitted to sway toward the right with a corresponding indication of the pointer 53. If the tension increases, the arm 44 tends to sway toward the left, the spring

51 is increasingly compressed and the pointer 53 moves toward the right. For any desired degree of tension in the thread the rod 47—48 may be adjusted to bring the pointer to the index pin 54. Having thus adjusted the indicating mechanism the operator is advised during each second of the winding operation whether the tension has slackened or increased from the desired standard. As already intimated the industry now requires hard cores that must be wound with a high degree of tension. Accordingly, if the pointer 53 is deflected at any time away from the index pin 54, the operator is warned that the core being wound will not be up to the required standard of hardness and immediate steps may be taken to remedy the unsatisfactory condition. The waste of winding commercially unsatisfactory cores is therefore obviated.

As in the machine of said patent above identified, the illustrated machine includes an arm 60 fast to a transverse shaft 61 journalled in the panel 10 and carrying a detector roll 62 which is arranged to run upon the upper side of the core being wound. As the diameter of the core increases this arm 60 is lifted by the core itself. The shaft 61 is rocked and an arm 63 secured to the shaft 61 behind the panel 10 is correspondingly lifted. The arm 63 is normally urged downwardly by a tension spring 64 and it is connected through a bent rod 65 to mechanism set for shifting the rod 19 of the clutch shipper when the diameter of the core has reached the dimension at which the winding operation should be terminated. A handle 66 is pivotally mounted upon the front of the panel and provided with a roll in position to engage the lower edge of the arm 60 for raising the same and getting the detector roll out of the way when the completed core is to be removed and a new core is to be placed in starting position.

The shaft 45, already referred to as carrying the arm 44, at its rear end is provided with a horizontal arm 67 and this is connected through a vertical rod 68 to another arm 69 also connected to the clutch-tripping mechanism and forming part of a thread-brake stopping mechanism. The arm 44, therefore, has two functions. It serves as a portion of the indicating mechanism for indicating the running tension in the thread, and it also serves as a part of the thread-brake stopping mechanism in that its movement toward the right as suggested in Fig. 2 in the event of thread breakage will at once operate to throw the shipper 17 and disengage the clutch and bring the machine at once to rest.

The manner in which the machine is used will be understood from the foregoing description but may be summarized as follows. The indicator rod 47—48 is adjusted as to length to bring the pointer 53 opposite the index pin 54 when the elastic thread passing over the guide roll 43 is tensioned to the proper degree for the work in hand. The hand lever 39 is then depressed, freeing the brake band 33 from the drum 32 and leaving the tension drum free to spin. The end of the elastic thread is drawn from the spool 25 and carried 1½ turns about the circumference of the drum. It is then wound for two or three turns upon the core center. The handle 66 is next swung toward the right lifting the roll 62 out of the way and the core is placed in position upon the bight of the apron 13. The roll 62 is now positioned upon the core and the machine started by depressing the handle 22 whereupon the roll 12 is rotated, driving the apron 13 and

the roll 11 which has an endwise reciprocatory motion in addition to its rotation. The core is thus wound up to the desired diameter and with the necessary degree of tension. At the conclusion of the winding operation the lifting of the arm 60 operates to stop the machine and the operator is free to remove the completed core.

Having thus disclosed my invention and described an illustrative embodiment thereof I claim 10 as new and desire to secure by Letters Patent:

1. A winding machine of the class described including in its organization a pair of rotary supports for a core, a supply of elastic thread, a tension drum about the circumference of which 15 the thread passes on its way to the core, said drum being spaced from said supports and of such diameter that the length of thread upon it exceeds at all times the length of the thread between it and the core, and controlled means 20 for retarding rotation of said drum.

2. A winding machine of the class described including in its organization means for supporting and rotating a core to be wound, a tension drum having a wide flaring flange about which 25 thread passes on its way to the core, and thread-guiding means arranged to direct thread to varying points on the circumference of said drum.

3. A winding machine of the class described including in its organization means for supporting and rotating a core to be wound, a tension 30 drum having a wide flaring flange about which thread passes on its way to the core, a thread reel, and a guide roll rotatable upon an axis not perpendicular to the axis of the tension drum and 35 oblique to the axis of the reel arranged to direct thread to varying points on the tension drum as the thread is drawn from varying points in the reel.

4. A winding machine including means for supporting and rotating a core, a tension device 40 about which elastic thread is passed on its way to a core, and means operating between the core and said device for indicating the degree of tension in the thread.

5. A winding machine including means for supporting and rotating a core, a tension device from 45 which elastic thread passes on its way to the core, a fixed index, and adjustable means cooperating therewith to indicate variations in the tension of the thread from a predetermined standard.

6. A winding machine including means for supporting and rotating a core, a tension device from 50 which elastic thread passes on its way to the core, a roll-carrying arm controlled in its position by the thread, a spring operated device acting on the arm in opposition to the pull of the thread, a pointer adjustably connected to the arm, and an index cooperating with the pointer.

7. A winding machine including means for supporting and rotating a core, a tension device from 55 which elastic thread passes on its way to the core, a roll-carrying arm controlled in its position by the thread, a spring actuated rod adjustably extensible and arranged to urge the arm away from the core, a pivotally mounted pointer operated by said rod, and a fixed index cooperating with the pointer.

8. A winding machine including means for supporting and rotating a core, a tension device from 60 which elastic thread passes on its way to the core, a spring actuated arm arranged to pull against the bight of the thread between the tension device and the core, and a tension indicator and automatic thread-break stopping mechanism both controlled by movement of said arm.

9. A winding machine including means for supporting and rotating a core, starting and stopping mechanism, a longitudinally movable rod for controlling said mechanism, a handle mounted to swing about an axis adjacent to the core-supporting means, and a pivoted contact piece disposed in wedging relation to said handle and arranged in its movement to operate said rod.

10. A winding machine having a frame which presents a vertical face, core-supporting rolls pro-

jecting forwardly from said face, a tension drum of greater diameter than the combined core-supporting rolls mounted to rotate in front of said face, and tension indicating mechanism constructed and arranged to act on thread passing from the tension drum to the core and including a pointer located upon the opposite side of the tension drum from the core-supporting rolls.

10

CHARLES R. SIBLEY.
